UNITED STATES PATENT OFFICE.

GEORGE C. KNAUFF, OF CHICAGO, ILLINOIS, ASSIGNOR TO EDMUNDS & JONES CORPORATION, OF DETROIT, MICHIGAN, A CORPORATION OF NEW YORK.

SOCKET FOR INCANDESCENT LAMPS.

1,263,075.

Specification of Letters Patent. Patented Apr. 16, 1918.

Application filed December 9, 1915. Serial No. 65,957.

To all whom it may concern:

Be it known that I, GEORGE C. KNAUFF, citizen of the United States, residing at Chicago, in the county of Cook and State of Illinois, have invented certain new and useful Improvements in Sockets for Incandescent Lamps; and I do hereby declare the following to be a full, clear, and exact description of the invention, such as will enable others skilled in the art to which it appertains to make and use the same.

My invention relates to fittings for incandescent electric lamps, its general objects being to provide simple, cheap and effective means for detachably but firmly connecting such a lamp to a socket, and for affording a simple and firmly held but detachable cover adapted either to disclose or conceal the luminous part of the lamp; also, to provide a construction in which the body of the lantern or lamp-inclosing part of the appliance is made integral with one of the contacting or current-carrying portions of the appliance and integral with some of the elements required for interlocking the detachable appliance in the socket. Also to provide means for preventing a loosening of the interlocked parts by jarring, but without having these means adapted to wedge in the socket or to distort the latter out of its normal shape. Further objects will appear from the following specification and from the accompanying drawings, in which

Figure 1 is an elevation of a socket having one embodiment of my invention attached thereto.

Fig. 2 is an enlarged longitudinal section through the axis of Fig. 1.

Figs. 3 and 4 are transverse sections through Fig. 2 along the lines 3—3 and 4—4 respectively.

Fig. 5 is a fragmentary elevation similar to Fig. 1 but showing another embodiment of my invention.

While the appliance of my invention may be embodied in many different types and used in connection with various forms of lamps and sockets, it is particularly adapted for use in connection with the lamps used on and about automobiles and is shown in such embodiments in the drawings. Thus, in the first four figures, my appliance is shown as used in connection with a dash-board socket 1 and an incandescent lamp 2, both of the so-called single pole construc-

tion, that is to say, the construction in which one terminal of the circuit is grounded to the metal socket portions so as to save wiring. In this case, the socket 1 has a cylindrical portion which carries an insulating body 3 supporting a wire terminal 4 metallically connected to a spring-pressed plunger 5 projecting toward the mouth of the socket, which mouth has a flange 6 for securing the socket to a dash-board. Extending rearwardly from the said mouth of the socket, the casing of the latter has diametrically opposite slots 7 each provided at its rear end with a return bend affording a seat for receiving a projection 8 upon the base 70 of my appliance, each such projection being similar to the lateral projections 9 upon the base of the lamp 2. The latter projections 9 are anchored in similarly shaped slots 10 in a cylindrical inner shell 11 soldered into 75 the outer casing 12 of my appliance, which inner shell has mounted in it an insulating body 13 carrying interconnected contact elements 14 and 15 contacting respectively with the plunger 5 and with the axial contact tip 80 16 on the base of the lamp 2.

The outer casing 12 extends in both directions beyond the ends of the cylindrical shell 11 and rearwardly of the latter is preferably diametrically contracted into a contracted end portion 17 adapted freely to enter the bore of the socket 1, the projections 8 being preferably formed integral with the said contracted end portion 17. Threaded upon the casing 12 adjacent to its said contraction is a nut 18 which may be screwed against the flange 6 so as to lock the projections 8 in the said seats of the slots 7, this nut being preferably undercut as shown in Fig. 2 so as to engage the flange 6 at 95 some distance from the casing 12, thus preventing the nut from wedging in the rounded juncture of the flange with the socket casing and also preventing a distorting of the socket by such a wedging.

The forward end of the casing 12 is enlarged considerably in diameter and preferably equipped with a peripheral flange 19 adapted to conceal the rear end of the cover 20 which I shall describe hereafter, and the 105 part of the casing 12 extending forwardly of this flange has a slot 21 affording an aperture through which the light of the lamp 2 may issue. Fitted over this forward part of the casing 12 is a cover 22 closed at its 110

forward end and provided with an aperture corresponding to the slot 21, so that when the cover is in one position, these apertures will align as in Fig. 1 to disclose the luminescent part of the lamp. However, by rotating the cover half way, so as to bring the lateral apertures out of alignment as in Fig. 3, the lamp will be concealed. To prevent the cover 22 from being jarred out of the desired position, I preferably provide both this cover and adjacent parts of the casing 12 with interlocking formations, as for example, by equipping the cover with a spring finger 23 entering an indentation 24 in the said casing when the lateral apertures are aligned and entering an opposite indentation 25 when the said apertures are out of alignment. It will be obvious from Figs. 2 and 4 that this interlocking will prevent the cover from being rotated by the jarring of the vehicle on which the appliance is used, although permitting the cover to be forcibly rotated and likewise allowing the cover to be detached by the application of a sufficient power to overcome the grip of the spring finger in one of the said indentations. However, I do not wish to be limited to the use of circumferentially spaced indentations as portions of the cover locking elements, nor to other details of the construction herein disclosed, since this construction might be modified in many ways without departing from the spirit of my invention. For example, the indentations 24 and 25 might be replaced by a single peripheral groove 26 (as in Fig. 5) entered by the spring finger 23, accidental rotation of the cover being prevented by the friction of this finger in the said groove. So also, it is to be understood that the pictured embodiments, representing so-called "trouble lamps" are illustrative of some, but by no means of all of the practical embodiments of my invention.

I claim as my invention:

1. In a socket for an incandescent lamp, a substantially cylindrical inner shell equipped at one end for holding the lamp, an outer

casing fast upon said shell and entirely housing the latter and extending beyond the latter at both ends, said casing being 50 enlarged at one end to house the bulb of the lamp and contracted at its other end to a bore equal to and forming a continuation of the bore of said inner shell, an insulating body housed jointly by the said continuation parts of both bores, and a contact element extending through the insulating body longitudinally of the said bores for conveying current to a terminal of the lamp. 55

2. The combination with a socket having 60 as circuit terminals a substantially cylindrical portion and a contact member disposed axially of said socket, of an incandescent lamp, and a lantern casing housing said lamp and electrically connecting one terminal thereof with the said cylindrical socket portion, said lantern casing having in integral formation a contracted end portion entering said cylindrical portion and a laterally apertured housing normally incasing 70 the bulb of said lamp, the said contracted end portion and socket being equipped with relatively interlocking formations; and a nut threaded upon said casing and engaging said socket to prevent a disengagement of 75 the said formations.

3. The combination with a socket having 80 as circuit terminals a substantially cylindrical portion and a contact member disposed axially of said cylindrical portion, of an incandescent lamp, and a lantern casing housing said lamp and electrically connecting one terminal thereof with the said socket, said lantern casing having in integral formation a contracted end portion entering said cylindrical portion and a laterally apertured housing normally incasing 85 the bulb of said lamp, the said contracted end portion and socket being equipped with relatively interlocking formations; and a nut threaded upon said casing and engaging 90 said socket to prevent a disengagement of the said formations.

GEORGE C. KNAUFF.
